FIG. 1

FIG. 2

FIG. 3

FIG. 4

FIGURE 1 is a side perspective view of a floodlight or similar article showing my new design with the coupling element fragmentarily shown for ease of illustration.

The semi-circular broken lines on the face of the concave reflector represent conventional peening.

FIGURE 2 is a side elevational view of the floodlight shown in FIGURE 1.

FIGURE 3 is a top plan view of the floodlight shown in FIGURE 1.

FIGURE 4 is a elevational view of the front of the floodlight shown in FIGURE 1.

The dominant features of my design reside in the portions shown in full lines.

I claim:

The ornamental design for a floodlight or similar article, as shown and described.
